UNITED STATES PATENT OFFICE.

WILLIAM W. FLEWELLING, OF SELMA, CALIFORNIA.

DESIGN FOR AN AXLE-BOX.

SPECIFICATION forming part of Design No. 32,178, dated January 30, 1900.

Application filed December 21, 1899. Serial No. 741,191. Term of patent 7 years.

To all whom it may concern:

Be it known that I, WILLIAM W. FLEWELLING, a citizen of the United States, residing at Selma, in the county of Fresno and State of California, have invented and produced a certain new and original Design for an Axle-Box; and I do declare the following to be a full, clear, and exact description of the invention, such as will enable others skilled in the art to which it appertains to make and use the same.

The invention relates to a new and original design for an axle-box; and it consists of a design of the shape and configuration shown in the accompanying drawing, in which I have represented my invention in perspective.

The leading feature of the design comprises the cylindrical body portion *a*, tapering from one end to the other and having at one end screw-threads *b* and at the other end a tapered 20 rectangular block *c*.

What I claim is—

The design for an axle-box, substantially as herein shown and described.

In testimony whereof I have hereunto set 25 my hand in presence of two subscribing witnesses.

WILLIAM W. FLEWELLING.
